UNITED STATES PATENT OFFICE.

ANDREW MIRONUCK, OF MAX, NORTH DAKOTA.

GRAIN SIFTER.

Application filed November 21, 1923. Serial No. 675,983.

This invention relates generally to a cleaner or sifter for grains or other comminuted material, the invention having for an object to provide a novel machine of this type characterized by efficient operation and adjustability to meet varying conditions, my improved machine being particularly adapted for use in sifting lighter material from heavier, such as the cockle seeds which 10 become mixed with the wheat.

For further comprehension of the invention, and of the objects and advantages thereof, reference will be had to the following description and accompanying drawings, 15 and to the appended claims in which the various novel features of the invention are more particularly set forth.

Fig. 1 of the drawings is a central longitudinal vertical sectional view showing my 20 improved cleaner.

Fig. 2 is a transverse sectional view thereof taken on the line 2—2 of Fig. 1.

Fig. 3 is a detail side view of the adjustable cam for imparting reciprocating motion 25 to the screen.

Fig. 4 is a face view thereof.

As here embodied my improved sifter and cleaner comprises a rotary cylindrical member 10 composed of sheet metal having outwardly projected indentations 11 of suitable size spaced over all but the rear portion thereof, the rear portion of the member being in the form of a wire mesh element 10'. The member 10 is slightly inclined to the horizontal, the raised end being termed the forward end, this forward end being supported on an enclosing anti-friction bearing 12, carried by a standard 13. The lower end of this member 10 is supported, through the 40 medium of a spider 14, on a shaft 15 to which references will be presently made.

Located adjacent the raised end of the screen is a hopper 16 for the material to be screened or sifted, this hopper having its discharge mouth turned into the open end of the member 10. Fixed to this hopper, and extending longitudinally through the member 10 at a greater angle to the horizontal than the latter, is a chute or trough 17 on 50 which the cockle seeds, or other light material, drop after being carried up in the pockets formed by the indentations 11. The lower end of this trough extends into a frusto-conical element 10^a fixed to the lower end of the member 10, the material being conveyed by this element 10^a to a spout 17

below which a suitable receptacle may be placed. The cleaned material falls through the screen into a semicylindrical receptacle 19 placed beneath the member 10 and provided with a discharge spout 19'.

To assist in the screening or sifting action I have provided means whereby the screen is given a longitudinal reciprocatory motion as it revolves and to this end the hub of the 65 spider element 14 freely engages the shaft 15 and is shown as having a feather connection with the shaft 15 as at 14', this hub being extended in the form of a sleeve 20 which passes through a bearing standard 13' 70 and has fixed to its forward end a disk 21 carrying a pair of rollers 22. Fixed to an offshoot from the said standard is a novel cam element here shown as comprising a disk 24 facing the disk 21 and having hinged 75 thereto as at 25 two pairs of cam arms, the respective arms of each pair being indicated at 26 and 27 and extending toward one another from their hinge ends. These arms are inclined with respect to the face of the 80 disk so as to constitute the cam elements, and have their free ends overlapping each other and curved inward toward the face of the disk as shown. As will be understood, the face of the disk 24 is suitably recessed 85 to accommodate these arms.

Threaded through the disk 24 in position to engage the said overlapped ends and form abutments for the arms, are screws 29 which may have lock nuts such as 30 thereon. Tension springs 31 which pass through suitable apertures in the disk 24 keep the arms 26, 27 pressed against the screws 29. It will be apparent that by adjusting these screws the degree of rise of the cam, and in consequence 95 the amount of reciprocatory movement imparted to the screen will be varied. Surrounding the sleeve element 20, and bearing between the standard 13' and the disk 21 is a coiled expansion spring 33 which acts to move the screen in one direction. Upon the end of shaft 15 a crank handle 35 is placed for purposes of rotation, a pulley 36 being also indicated as mounted on said shaft to permit of the same being power driven when 100 desired.

It is believed that the manner of operation and use of my improved screening and sifting machine will be readily understood from the above description. The material 110 to be cleaned is placed in the hopper 16, which is provided with a suitable control

valve 40 which may be of any desired type, and which is properly regulated to cause a desired flow of material into the member 10. The latter is then caused to revolve, by rotating shaft 15, and at the same time is given a reciprocatory motion through the action of the cam arms 26, 27 on the rollers 22, so that a thorough shaking and agitating of the material is effected as it travels along the said member. The lighter material will be carried upward by the pockets 11 dropping on the trough 17 and being discharged from the end of the member 10.

While I have illustrated and described a preferred embodiment of my invention it is to be understood that I do not limit myself to the precise construction herein disclosed and that various changes and modifications might be made therein without departing from the spirit and scope of the invention as defined in the appended claims.

Having thus described my invention what I claim as new and desire to protect by Letters Patent of the United States is as follows:

1. A reciprocating means for the rotary drum of a grain sifter, comprising a bearing, a sleeve passing through said bearing, a disk fixed to the forward end of said sleeve, rollers mounted on the front face of said disk, a standard offshot from said bearing, a disk fixed to said standard, a pair of cam arms hinged to said latter disk, said cam arms extending towards one another from their hinged ends, inclined with respect to the face of the disk so as to constitute cam elements, the free ends of said cam arms overlapping, and curved inwards towards the face of the latter mentioned disk, adjusting screws threaded through said latter disk, abutting said cam arms, tension springs passing through apertures in the lat-

ter disk, and having one end fixed to said disk, and the other to said cam arms to press the cam arms against the said adjusting screws, a shaft passing through said sleeve, and feathered thereto, allowing longitudinal freedom, and a coiled expansion spring surrounding said sleeve, and acting between the said bearing and the first mentioned disk fixed to the forward end of said sleeve, said coiled expansion spring urging said sleeve and attached disk in one direction.

2. A reciprocating means for the rotary drum of a grain sifter, comprising a bearing, a sleeve passing through said bearing, a disk fixed to the forward end of said sleeve, rollers mounted on the front face of said disk, a standard offshot from said bearing, a disk fixed to said standard, a pair of cam arms hinged to said latter disk, said cam arms extending towards one another from their hinged ends, inclined with respect to the face of the disk so as to constitute cam elements, the free ends of said cam arms overlapping, and curved inwards towards the face of the latter mentioned disk, adjusting screws threaded through said latter disk, abutting said cam arms, locking nuts engaged on said adjusting screws, tension springs having one end fixed to said latter disk, and the other to said cam arms to press the cam arms against the said adjusting screws, a shaft passing through said sleeve, and feathered thereto, allowing longitudinal freedom, and a coiled expansion spring surrounding said sleeve, and acting between the said bearing and the first mentioned disk fixed to the forward end of said sleeve, said coiled expansion spring urging said sleeve and attached disk in one direction.

In testimony whereof I have affixed my signature.

ANDREW MIRONUCK.
